(57) **CLAIM**

The ornamental design for a top divider panel for an office partition, as shown and described.

DESCRIPTION

FIG. 1 is a perspective view of a top divider panel for an office partition according to our new design;

FIG. 2 is a front/rear view thereof, wherein the front and rear views are identical;

FIG. 3 is a left/right side view thereof, wherein the left and right side views are identical; and,

FIG. 4 is a top view thereof.

Features shown in dashed lines form no part of the claimed design.
